United States Patent Office.

GEORGE G. MORRIS, OF BOSTON, MASSACHUSETTS, ASSIGNOR TO HIMSELF
AND WILLIAM W. EASTHAM, OF SAME PLACE.

Letters Patent No. 99,338, dated February 1, 1870.

IMPROVED PAINT-BRUSH.

The Schedule referred to in these Letters Patent and making part of the same.

To all whom it may concern:

Be it known that I, GEORGE G. MORRIS, of Boston, in the county of Suffolk, and State of Massachusetts, have invented an Improvement in Paint-Brushes; and I do hereby declare that the following, taken in connection with the drawings, which accompany and form part of this specification, is a description of my invention, sufficient to enable those skilled in the art to practise it.

In the manufacture of paint-brushes, it is customary to form a wire ferrule, by winding a coil of wire and soldering the adjacent wires together, thus making a ring or ferrule, and to fill this ferrule with the but ends of the bristles, driving through the centre of the bristles in the ring the brush-handle, the large end of which compacts the bristles between it and the inner surface of the wire ferrule, the ends of the bristles being flush with the top of the ring, and being covered with cement.

Brushes have been made for many years with a circular cap interposed between the ends of the bristles and the upper opening in the wire ring, said cap being crowded into the end of the ring, and the ends of the bristles butting against its inner surface. These caps have been made of wood and of cork, and also of a cement composed of sand and rosin; or sawdust and rosin.

Lately brushes have been, to some extent, manufactured having such caps made of leather, as shown in the patent granted to D. White, November 24, 1868. The only difference between the construction of such White, and brushes made for years previous to said White's patent, being that said White's disk or cap is made of leather, while in the previous brushes they were made of wood, cork, or composition.

In my invention, I construct a brush with a disk or cap covering the tops of the bristles, such cap being made of pasteboard, applied in a moist or saturated condition, it being filled with a solution of shellac, which not only cements the bristles firmly in position, but causes the disk or cap to become very hard, rigid, and impervious.

It is in this construction that my invention consists, or in a paint-brush having the bristles surmounted by

a cap made of pasteboard, permeated with shellac, and applied while in a pliant, moist, and viscid condition, the cap adhering firmly to the bristles when it becomes dry, thereby not only strengthening the brush, but forming a cap which is impermeable to the passage of the oil and turpentine contained in the paint.

The drawings represent a brush embodying my improvement.

A shows the brush in side elevation, the wires being broken away at one point to show the edge of the cap.

B is a sectional elevation of the brush.

a denotes the bristles;

b, the wire ferrule;

c, the handle; and

d, the cap.

The bristles being properly prepared in the customary manner, and the but-end of the bunch being placed in the ferrule, the ends are covered with a cement made of white lead, litharge, &c. The pasteboard cap having been prepared by soaking in the shellac solution, and being in a soft, viscid, and pliable condition, is pressed into the top of the ferrule, the bristles abutting against its inner surface. The point of the handle is then passed through the centre of the free ends of the bristles, and through the ferrule and cap, and is driven up through the cap until the large end enters the cap-hole, and, expanding the cap, presses its periphery tightly against the inner surface of the cap.

The brush being then allowed to dry, the shellac and cement fasten the cap and bristles firmly in place, and the pasteboard becomes hard and impermeable, as before set forth, not shrinking, as leather will do, under similar treatment, and not becoming pervious to oil and turpentine, under the permeable action of which leather becomes soft, and soon breaks away from the cap and bristles.

I claim a paint-brush, having a cap, d, made of pasteboard, treated and applied and rendered hard and impermeable, substantially as described.

Executed December 13, A. D. 1869.

GEORGE G. MORRIS.
